HEDGE TRIMMER

George L. Congdon, Fort Atkinson, Wis., assignor to
McGraw-Edison Company, Milwaukee, Wis., a cor-
poration of Delaware

Filed Aug. 28, 1968, Ser. No. 13,300

Term of patent 14 years

Int. Cl. D8—01

U.S. Cl. D8—8

FIG. 1

FIG. 2

FIG. 4

FIG. 5

FIG. 6

FIG. 1 is a perspective view of a hedge trimmer having my improved design;

FIG. 2 is a side elevational view of the hedge trimmer;

FIG. 3 is a top plan view of the hedge trimmer;

FIG. 4 is an elevational view of the hedge trimmer as seen from the blade end of the hedge trimmer;

FIG. 5 is an elevational view of the hedge trimmer as seen from a handle of the hedge trimmer; and

FIG. 6 is a bottom plan view of the hedge trimmer, having part of the construction broken away to show the hollow underside of the forward handle.

The dominant features reside in the solid line portions.

The broken lines showing a portion of a blade are for illustrative purposes only, same being shortened for convenience of illustration.

I claim:

The ornamental design for a hedge trimmer, as shown and described,
